UNITED STATES PATENT OFFICE

WILLIAM H. BLAKE, OF ATTLEBORO, MASSACHUSETTS, ASSIGNOR TO JAMES E. BLAKE
CO., A CORPORATION OF MASSACHUSETTS

HAIRBRUSH

Application filed December 26, 1928. Serial No. 328,487.

My invention relates to hair brushes of that type which is purposed to house a comb, wherein a metal shell carries a bristle block.

Heretofore this type of brush has contained a backing block filling the space between the bristle block and the shell and provided with a longitudinal hole for the reception of the comb. This filler block was expensive to construct and difficult to fit to the contour of the shell because its construction required manual formation and could not be shaped by turning tools.

The essential objects of my invention are to overcome the above disadvantages and provide a more efficient means for guiding and retaining the housed comb, as well as lighten the weight of the brush.

With these objects in mind my invention consists in such parts and in such combinations of parts as fall within the scope of the appended claims.

In the accompanying drawings which form a part of this specification

Figure 1 is a plan view of my hair brush, 25 Figure 2, a vertical longitudinal section on line 2—2 of Figure 1,

Figure 3, a horizontal longitudinal section of the same,

Figure 4, a transverse section on line 4—4 30 of Figure 1, and

Figure 5, a perspective view of the comb retaining member.

Similar reference characters indicate similar parts throughout the views.

35 My brush includes a back 12 comprising a body portion 13 and handle portion 14. The usual metal shell 15 forms a casing for the top and side of the body, and a tubular extension of the shell forms the handle portion 40 14 of the back. The lower open portion of the casing or metal shell body 15 is provided with an inturned peripheral flange 17 which tightly embraces and retains the usual bristle block 18 provided with holes 19 for the reception of the bristle tufts 20. It will be observed that the upper surface of the block 45 18 is flat and in alignment with the handle portion 14, as well as spaced from the metal top of the body portion of the brush.

50 Fixed to the flat surface of the block is a

tubular transversely rectangular guide 22, composed of thin metal or celluloid bent up into final form, and comprising a flat oblong top wall 23, and downwardly directed side walls 24, and an open bottom. Integral with the lower portion of the sides are horizontal lateral flanges 25 provided with perforations 26 for the reception of nails, screws, or rivets 27 by means of which the member 22 is attached to the block and in longitudinal alignment with the hollow handle 14, and has one end registering with an oblong opening 28 in the forward end of the body casing. The member 22 is shallow to insure that a flat comb 29, fitted to slide longitudinally through the guide in contact with the block shall nevertheless have sufficient frictional engagement with the guide and block to be retained in any desired portion therein.

The comb is preferably of greater length 70 than the brush so that when one end of the former abuts against the closed end of the brush handle, the other end of the comb projects beyond the opposite end of the brush through the opening 28.

Since the tubular member 22 is composed of sheet metal or celluloid its walls are thin and have a slight degree of expansibility or resiliency, which insures adequate retention of the comb, and accommodates combs of 75 slightly varying dimensions.

I claim:

1. In a hair brush, a shell, a retaining flange upon the shell, a block engaged by the flange, bristles in the block, and a longitudinal member fixed to the block with its top and sides spaced from the shell to form a guide, and a comb slidably mounted in the guide, and engageable at one end with the shell.

2. In a hair brush, a shell, a retaining flange upon the bottom of the shell, a block embraced by the flange, bristles in the block, a resilient member fast to the block to form a guide, and a comb slidably mounted in the guide.

3. In a hair brush, a shell comprising a body portion and a tubular extension having a closed end, a flange upon the bottom of the body portion, a block in the shell engaged by

the flange and having a flat top in the plane of the extension, bristles in the block, a longitudinal member comprising thin walls fast to the top of the block in alignment with the extension and forming a guide, and a comb detachably mounted in the guide extending the length of the extension.

4. In a hair brush, a shell provided in its bottom with an opening, a block fixed in the opening with its top spaced from the top of the shell, bristles in the block, a longitudinally-disposed guide within the block comprising a thin top wall, spaced from the top of the shell, thin side walls and lateral flanges upon the side walls fixed to the top of the block, and a comb detachably inserted in the guide engageable at one end to the shell.

In testimony whereof I have affixed my signature.

20
